UNITED STATES PATENT OFFICE

SAMUEL A. MONTGOMERY AND JOHN A. HUBBARD, OF WOOD RIVER, ILLINOIS, AS-SIGNORS TO STANDARD OIL COMPANY (INDIANA), OF CHICAGO, ILLINOIS, A CORPORATION OF INDIANA

SULPHURIC ACID CONCENTRATION

Application filed October 24, 1929. Serial No. 402,056.

This invention pertains to a sulphuric acid concentration system and it relates more particularly to the method of heating sulphuric acid for a vacuum concentrator.

5 The object of our invention is to increase the capacity and the efficiency of commercial sulphuric acid concentrators, particularly of the Simonson-Mantius type.

A further object is to provide a vacuum 10 concentration system for sulphuric acid in which the heating is effected under atmospheric pressure so that ordinary lead pipe heating coils may be used and the danger from small leaks or weak spots in said coils 15 is minimized.

A further object is to provide an improved 20 method of heating the first stage of a vacuum concentrator to keep the acid constantly above its boiling temperature, thereby avoiding periods of idleness or slow evaporation.

Our invention may be briefly characterized 25 as a system in which weak sulphuric acid is preheated under atmospheric pressure to a temperature which will cause the acid to boil when it is introduced into the vacuum concentrator. When the acid is passed through a reducing valve into the evaporator it immediately boils without foaming and drives off a large amount of diluent water.

30 Heretofore cold acid has been charged into the concentrator and until this acid reached the boiling point the power required for maintaining the vacuum was largely wasted. The heater in the vacuum concentrator had 35 to be very strong and free from minute leaks or weak spots because it was important that the vacuum remain unimpaired. We avoid periods of idleness in the evaporator and the use of expensive heating coils by preheating 40 the sulphuric acid in a separate receptacle which is maintained under normal pressure.

Our invention will be better understood 45 from the accompanying drawing which diagrammatically illustrates a preferred embodiment.

In the process of treating mineral oils a large amount of weak sulphuric acid, about 30° Bé. is formed. Before this acid can be 50 used for further treatment it must be con-

centrated to a specific gravity of about 66° Bé. The first step of the concentration has heretofore been the introduction of the acid into the first stage of the vacuum concentrator where heat is applied to raise the acid 55 to a boiling temperature. The time required for reaching the boiling temperature is usually about four or five hours after the beginning of the run and although the vacuum is maintained during this time it accomplishes 60 practically nothing. After evaporation has proceeded for eight or ten hours, additional acid is added to restore the original level in the evaporator. This makeup acid lowers the temperature below the boiling point and 65 the efficiency of the evaporator is again impaired by a period of relative idleness.

We provide a preheater for the weak acid as illustrated in the drawing. The heater may consist of a lead coil through which 70 steam may be circulated at atmospheric pressure. The heating coils used in the vacuum concentrator must meet rigid specifications but those used in our preheater may be of ordinary construction because both the steam 75 and the acid bath are at substantially atmospheric pressure so that small leaks or weak spots are immaterial. The acid entering the heater is usually from 50° to 100° F. It is heated to about 150° to 200° F. at atmospheric pressure and then passed through a reducing valve to the first stage of a vacuum concentrator which is maintained under a vacuum of about 26 inches to 27 inches of mercury. Under this reduced pressure the 80 liquid boils vigorously but without undue foaming and a rapid evaporation is accomplished. The acid may be continuously supplied through a reducing valve to maintain the most effective volume in the concentrator. 85 90

The evaporation in the concentrator may be continued by heating coils mounted therein. We may avoid, however, the use of steam coils in the vacuum system by returning acid to the heater under atmospheric pressure and 95 carrying out the heating and evaporating steps as illustrated in the drawing.

While we have described a preferred embodiment of our invention it is understood that we are not limited to the details therein 100

set forth except as defined in the following claims.

We claim:

1. A continuous process for concentrating a dilute solution under reduced pressure which comprises heating the solution at normal pressure to a temperature above the boiling point of the solution at said reduced pressure, transferring said heated solution to a concentrator, maintaining a reduced pressure in said concentrator, removing a portion of said solution from said concentrator, subjecting the removed portion to increased pressure, reheating said portion to a temperature above the boiling point of the solution at said reduced pressure, and returning said reheated portion with additional preheated solution to said concentrator whereby the latent heat of evaporation is supplied by the sensible heat of said preheated and reheated solutions to maintain the solution in the concentrator at boiling temperature.
2. The continuous method of concentrating a dilute solution under reduced pressure which comprises maintaining a body of said solution under reduced pressure, separately maintaining a second body of said solution at a higher pressure and heating said second body of solution to a temperature above the boiling point of the solution at reduced pressure, transferring the heated solution at the higher pressure to the body of liquid at reduced pressure to maintain the latter at a temperature above its boiling point at said reduced pressure, recycling part of said low pressure solution into said high pressure solution and maintaining substantially constant the volume of the body of solution at reduced pressure.

Signed at Wood River, Illinois, this 13th day of Sept., 1929.

JOHN A. HUBBARD.
